(57) **CLAIM**

The ornamental design for a cryosurgical probe, as shown and described.

DESCRIPTION

FIG. 1 is a perspective view of a cryosurgical probe, showing our new design;

FIG. 2 is a side view thereof;

FIG. 3 is a top view thereof;

FIG. 4 is a bottom view thereof; and,

FIG. 5 is a front view thereof; and,

FIG. 6 is a rear view thereof.

Portions of the cryosurgical probe shown in broken lines form no part of the claimed design.
